RELAY MEANS FOR HIGHWAY CROSSING SIGNAL SYSTEMS

Original Filed Jan. 20, 1931

FIG. 1.

FIG. 2.

INVENTOR
W. S. Henry,
BY *Neil D. Preston*,
HIS ATTORNEY

UNITED STATES PATENT OFFICE

WILLIAM S. HENRY, OF COLDWATER, NEW YORK, ASSIGNOR TO GENERAL RAILWAY SIGNAL COMPANY, OF ROCHESTER, NEW YORK

RELAY MEANS FOR HIGHWAY CROSSING SIGNAL SYSTEMS

Original application filed January 20, 1931, Serial No. 509,976. Divided and this application filed December 3, 1931. Serial No. 578,701.

This invention relates in general to relay means for signalling systems, and has more particular reference to means particularly suited to highway crossing signal systems.

5 The present application is a division of application Ser. No. 509,976 filed January 20, 1931.

In highway crossing signals employing usual interlocking relays, if a train enter one 10 of the usual detector track sections, at one side of a highway, at a time when the other detector track section at the other side of the highway is shunted, or de-energized, or open circuited, from any cause whatsoever, the 15 interlocking relay for the side of the entering train is already latched up, and hence the train cannot warn of the danger due to its approach to the highway by energizing the highway crossing signal. In other words, 20 there is no protection afforded by the highway signal against a train approaching the highway under such conditions. The short-circuiting or shunting referred to, of one of the detector track sections, can occur due to a 25 maintainer testing the track circuit, to a sleigh runner or the like over the track rails, or to other means.

One object of the present invention is to provide a relay organization particularly 30 adapted to be used in a system for protecting against a combination of circumstances such as pointed out above.

Further objects, purposes and characteristic features will appear as the description 35 progresses, reference being made to the accompanying drawing showing, solely by way of example, and in no manner in a limiting sense, one form which the invention can assume. In the drawing:—

40 Fig. 1 is a diagrammatic view showing one form of the invention.

Fig. 2 is a fragmentary diagrammatic view showing structural features of the invention.

The invention, as shown in the drawing, 45 comprises an interlocking latching relay IR including two pivoted armatures 4 and 5, biased by gravity to move downwardly against stops 6 and 7 and held in the full line position, shown in Fig. 2, when armature 50 8 is energized.

As shown in Fig. 2, contact carrying armatures 9 and 10 of relays TR⁰ and TR¹ respectively, are so positioned with respect to the pivoted armatures 4 and 5 as to be locked against moving to full released position by 55 the armatures 4 and 5, if such armatures are down, and have been first released. When de-energized in such circumstances, the armature of relays TR⁰ and TR¹ move toward full released position, but are prevented from 60 moving far enough to close their back contacts.

The operation of the interlocking or latching relay IR, and the track relay TR⁰ and TR¹, is diagrammatically shown in Fig. 2, 65 from which it can be seen that the interlocking relay can lock either or both of the other two relays against moving to full released position, i. e., against closing their back contacts, if the interlocking relay is first de-energized. Furthermore, each of the relays TR⁰ and TR¹ can lock the respective cooperating armature of the interlocking relay, in released position, if such relay TR⁰ or TR¹ is de-energized after relay IR has been de- 70 energized and has released its armature. 75

The above rather specific description of one form of the invention has been given solely by way of illustration, and is not intended, in any manner whatsoever, in a limiting sense. Obviously, this invention can assume many different physical forms, and is susceptible of numerous modifications, and all such forms and modifications, are intended to be included by this invention, as come 80 within the scope of the appended claims. 85

Having described my invention, I now claim:—

1. In combination, an operating relay, a latching relay, an armature for each relay, 90 the armature of the latching relay being arranged when released, to prevent release of the operating relay armature but ineffective to prevent the picking up of the operating relay armature, and the operating relay armature being ineffective to prevent release of the latching relay armature, but effective, when released, to prevent pick up of the latching relay armature. 95

2. In a relay organization, two spaced op- 100

erating armatures, independent means for operating the armatures, a latching armature for each of the operating armatures, means to operate the latching armatures, each latching armature, when released, being latched in released position by its operating armature when in released position.

3. In a relay organization, two spaced operating armatures, independent means for 10 operating the armatures, a latching armature for each of the operating armatures, means to operate the latching armatures, each latching armature, when released, being latched in released position by its operating armature when in released position, and each latching armature when in released position, latching its operating armature 15 against moving to released position.

4. In a relay organization, two spaced operating armatures, independent means for 20 operating the armatures, a latching armature for each of the operating armatures, means to simultaneously operate the latching armatures, each latching armature, when released, being latched in released position by its operating armature in released position.

5. In combination, an operating relay, a latching relay, an armature for each relay, the armature of the latching relay being arranged when released, to move into the path of, and to prevent release of the operating relay armature but ineffective to prevent the picking up of the operating relay armature, and the operating relay armature being ineffective in attracted position, to prevent release of the latching relay armature, but effective, when released, to prevent pick up 35 of the latching relay armature from its retracted position.

40 In testimony whereof I affix my signature.
WILLIAM S. HENRY.
